US00D649898S

(12) **United States Design Patent**
Yang

(10) **Patent No.:** **US D649,898 S**
(45) **Date of Patent:** **** Dec. 6, 2011**

(54) **LOW PROFILE ELECTRONIC ARTICLE SURVEILLANCE TAG**

D559,720 S 1/2008 Raymond
7,336,180 B2 2/2008 Sayegh et al.
7,400,254 B2 7/2008 Yang et al.

(75) Inventor: **Xiao Hui Yang**, Los Altos, CA (US)

(Continued)

(73) Assignee: **WG Security Products**, San Jose, CA (US)

Primary Examiner — Caron D Veynar
Assistant Examiner — George D Kirschbaum

(**) Term: **14 Years**

(74) *Attorney, Agent, or Firm* — Waters Law Group, PLLC; Robert R. Waters; Brian W. Foxworthy

(21) Appl. No.: **29/388,255**

(22) Filed: **Mar. 25, 2011**

(51) **LOC (9) Cl.** **10-05**

(52) **U.S. Cl.** **D10/106.91**

(58) **Field of Classification Search** D10/106.91, D10/106.9, 121; 340/572.8, 578.9, 572.1, 340/568.1, 825.54; D13/137.1, 137.2, 138.1; D8/354, 356, 364, 373, 380

See application file for complete search history.

FIG. 1 is a top view of the body of my new design for a low profile electronic article surveillance tag.

FIG. 2 is a bottom view of the body of my new design for a low profile electronic article surveillance tag.

FIG. 3 is a side view of the body of my new design for a low profile electronic article surveillance tag.

FIG. 4 is a side view of the cap of my new design for a low profile electronic article surveillance tag.

FIG. 5 is a top view of the cap of my new design for a low profile electronic article surveillance tag.

FIG. 6 is a bottom view of the cap of my new design for a low profile electronic article surveillance tag.

FIG. 7 is a first perspective view of the body and cap of my new design for a low profile electronic article surveillance tag in relation to each other.

FIG. 8 is a second perspective view of the body and cap of my new design for a low profile electronic article surveillance tag in relation to each other.

FIG. 9 is a first perspective view of the body and cap of my new design for a low profile electronic article surveillance tag in assembly; and,

FIG. 10 is a second perspective view of the body and cap of my new design for a low profile electronic article surveillance tag in assembly.
